UNITED STATES PATENT OFFICE.

GEORGE P. MACINTOSH, OF WAKEFIELD, MASSACHUSETTS.

FELLY-ENGAGING ANTISKID-CHAIN-ANCHORING MEANS.

Application filed October 10, 1921. Serial No. 506,585.

To all whom it may concern:

Be it known that I, GEORGE P. MACINTOSH, citizen of the United States, residing at Wakefield, in the county of Middlesex and 5 State of Massachusetts, have invented new and useful Improvements in Felly-Engaging Antiskid-Chain-Anchoring Means, of which the following is a specification.

This invention relates to an anti-skid device which includes a chain adapted to extend across the tire of a vehicle wheel and anchoring means attached to the wheel felly and adapted to engage the terminal links of the chain in such manner as to confine the 15 latter in its operative position.

The invention is embodied in certain improvements in the anchoring means, having for their object the prevention of an automatic separation of the chain from the felly 20 and the loss of the chain.

Of the accompanying drawings forming a part of this specification,—

Figure 1 is an edge view of one form of 25 anchoring means embodying the invention.

Figure 2 is a plan view of the same.

Figure 3 is a view similar to Figure 2, showing a different arrangement of the hooks hereinafter described.

Figure 4 is an edge view of the anchoring 30 means shown by Figure 3, and of a chain engaged therewith and a sectional view of a felly and its tire.

Figure 5 is a section on line 5—5 of Figure 3.

Figure 5^a is a view similar to Figure 5.

Figure 6 is a plan view of an anchoring means including two guarded hooks.

Figure 7 is an edge view of the anchoring means as shown by Figure 6.

Figure 8 shows an anchoring means made 40 in two parts, for use with fellys of maximum width.

Figures 9 and 10 show another form of anchoring means embodying the invention.

The same reference characters indicate the 45 same parts in all of the figures.

In the drawings, 12 represents a wheel felly and 13 an elastic tire thereon. The terminal links of an anti-skid chain 14 are engaged with an anchoring means embodying the 50 invention, attached to the felly, said means being adapted to hold the chain in the form of a loop extending from side to side of the felly, and across the tread face of the

tire, this being the operative position of the 55 chain. Said anchoring means in the embodiment of the invention shown by Figures 1 to 7, inclusive, includes an attaching base 15, bearing on and extending across the inner 60 surface of the felly, and bolted to the latter, 65 and a pair of hooks formed on said base.

In the embodiment of the invention as shown by Figures 1, 2, 3 and 4, the base is provided at one end with a guarded hook 65 adapted to be engaged with a terminal link 70 by a suitable manipulation of the latter, and to prevent automatic or accidental separation of the link from the hook and the loss of the chain, and at its opposite end with 75 an unguarded hook adapted to cooperate 80 with the guarded hook in securing the chain in its operative position. The guarded hook includes a curved neck portion 17 projecting outwardly from the outer side of the base 15, in the plane of the chain when the latter is in its looped operative position, and a terminal portion 18 overhanging the outer side of the base, and provided with flukes 19, projecting in opposite directions from 85 the plane of the neck portion, and formed to be engaged with a terminal link of the chain 14 by the manipulation illustrated by Figures 5 and 5^a. The link is first held, as shown by Figure 5, at right angles to the plane of the loop formed by the chain when 90 the latter is in its operative position, the link being then slipped over the flukes. The link is then swung to the dotted line position shown by Figure 5^a and shifted on to the neck portion 17 and allowed to depend therefrom. The chain is finally adjusted in the 95 form of a loop, as shown by Figure 4. The above-mentioned terminal link is now so engaged with the guarded hook that it can be separated therefrom, only by a reversal of the described movements, and cannot be automatically separated or cast off from the hook.

The unguarded hook includes a curved neck portion 21 projecting outwardly from the base 15 in the plane of the loop formed by the chain and an elongated finger-shaped terminal portion 22 overhanging the base. The form of the unguarded hook is such that, so long as the chain is intact, it is retained in its operative position by the co-operation of the two hooks. I do not limit myself to the conjoint employment of a 100 105

guarded and an unguarded hook, and may employ two guarded hooks, as shown by Figures 6 and 7.

The base 15 may be secured by bolts passing through holes 24 formed in it, or by bolts passing through holes in ears 15^a formed on the ends of the base and bearing on the sides of the felly as shown by Figure 4. The hooks may be diagonally arranged as shown by Figure 2, or in alinement with each other as shown by Figures 3 and 5.

As shown by Figure 8, each hook may have an independent base 15^b, each adapted to be bolted to a felly. The hooks and bases 15 shown by Figure 8, are adapted for use with very wide fellys.

As shown by Figures 9 and 10, the invention may be embodied in an anchoring means composed of a base 15^c, adapted to bear on the inner side of the felly, ears 15^d at opposite ends of the base, formed to bear on opposite sides of the felly, and to receive attaching bolts, and hooks projecting from said ears, the form of the hooks and their arrangement relatively to each other and to the loop formed by the chain being as in the previously described embodiments of the invention.

It will be seen that in each embodiment of the invention the hooks are coextensive with the plate or base whereby they are supported and project therefrom so that when the base is attached to the felly the hooks project out-

ward from the opposite sides of the felly. By virtue of this arrangement the end portions of chains whose terminal links are engaged with said hooks extend substantially straight across the sides of the felly as shown by Fig. 4.

I claim:

An anti-skid-chain anchoring means, adapted to hold a chain in the form of a loop extending across the tread of a wheel tire and across the opposite sides of the felly, comprising a base adapted to be secured to the inner face of the felly, said base being provided with hooks coextensive therewith and projecting therefrom to project outward from the opposite sides of the felly, so that the end portions of chains whose terminal links are engaged with said hooks extend substantially straight from the hooks across the sides of the felly, each hook being connected with the body of the base by a curved neck whereby the hook is directed backward and overhangs the base, said means including oppositely directed laterally extending flukes so arranged that a terminal link of the chain can only be engaged with the flukes by being arranged in a position substantially at right angles to that occupied by it after being passed onto said curved neck.

In testimony whereof I have affixed my signature.

GEORGE P. MACINTOSH.
